INTERRUPTERS FOR ENGINE SPARK-IGNITION APPARATUS

William Harold Cooksey, Walsall, England, assignor to Joseph Lucas (Industries) Limited, Birmingham, England

Filed June 12, 1959, Ser. No. 819,959

Claims priority, application Great Britain June 19, 1958
3 Claims. (Cl. 200—30)

This invention relates to an electric current interrupter mechanism for an engine spark-ignition apparatus of the kind in which the interrupter is mounted on a carrier having freedom of angular movement relatively to a fixed supporting member, the interrupter comprising a pair of contact pieces which are separable by the action of a rotary cam on a spring-loaded arm to which one of the contact pieces is attached. The angular movement of the interrupter serves to vary the ignition timing and may be effected manually or by a governor responsive to, for example, the pressure in the air-intake manifold of the engine.

When an interrupter mechanism of the said kind is in action the cam intermittently exerts on the arm associated with the movable contact piece a radially directed force which tends to produce an undesirable deflection of the plane of the interrupter carrier in consequence of the small amount of slackness which inevitably exists in the bearing by which the carrier is mounted on the supporting member. One effect of this deflection is to impair the desired smoothness of the angular movement of the carrier. Another is to cause unequal separation of the contact pieces with resulting irregularity of the ignition timing.

The object of the present invention is to provide an improved construction whereby the aforesaid disadvantages can be obviated.

An interrupter mechanism of the kind above specified and in accordance with the invention includes a triangular arrangement of three abutments which provide a three-point support between the interrupter carrier and the supporting member, two of which abutment pieces serve as fulcrum points and the third of which serves as a stop, and a spring loaded projection extending from the interrupter carrier through an aperture in the supporting member, the arrangement being such that the stop prevents tilting of the interrupter carrier relatively to the supporting member by the impacts of the cam.

In the accompanying drawings:

FIGURE 1 is a front elevation of an interrupter mechanism embodying the invention.

FIGURE 2 is a sectional side view on the line 2—2 of FIGURE 1.

FIGURE 3 is a sectional plan on the line 3—3 of FIGURE 1.

FIGURE 4 is a plan and FIGURE 5 a rear elevation of the mechanism.

FIGURE 6 is a perspective view illustrating a detail feature to be hereinafter described.

Referring to the drawings, the supporting member 10 consists of a metal plate of circular or other shape adapted to be secured within the housing of the mechanism by screws inserted through lugs 11. At the centre of this plate is formed an annular boss 12 which serves as the bearing for the interrupter carrier 13; the latter consisting of a metal plate of any convenient shape and having therein a circular aperture to receive the boss on the supporting member. On the said carrier plate is secured the fixed contact piece 14 of the current interrupter, and a post 15 which serves as the pivot for an arm 16 made from electrical insulating material. To this arm is attached a spring blade 17 on the free end of which is se-

2

cured the movable contact piece 18 which co-operates with the fixed contact piece 14. The arm is also loaded by a spring (partially shown at 16a) which serves to move the arm in the direction for closing the contact pieces together. On the arm is formed a tip 19 which co-operates with the rotary arm-actuating cam 20 whereby the contact pieces are intermittently separated.

On the interrupter carrier 13 is also formed an arm 21 for connection to any desired means for imparting angular movement to the carrier relatively to the supporting member for varying the ignition timing as above-mentioned.

In applying the invention to such mechanism there are secured to or formed on the rear of the interrupter carrier plate 13 three abutments 22, 23, 24 which bear against the adjacent face of the supporting member 10, the abutments being arranged in a triangular disposition as shown in FIGURE 1. The abutments 22, 23 serve as fulcrum points about which a slight tilt can be imparted to the plate 13 to bring the abutment 24 (which serves as a stop) into contact with the supporting member 10. The position of the abutment 24 is such that it is located on a radial line drawn through it and the tip 19 of the arm 16.

At a position adjacent to the stop 24 there is secured to the rear of the carrier plate 13 a projection 25 which extends through an arcuate slot 26 in the supporting member 10, and on this projection is formed or secured a head 27 which is shaped to present two surfaces 28 which are inclined in opposite directions at a small angle to the adjacent rear face of the supporting member. Also there is provided between the head and the supporting member a slipper 29 consisting of a thin metal plate which lies in contact with the supporting member. The slipper is shown separately in FIGURE 6. In it is formed a notch 30 through which passes the projection 25, and a slot 31 which receives one end of a tag 32 secured to the projection, and serving to hold the plate in position. Further, there are formed on the opposite side edges of the slipper a pair of tongue pieces 33 which abut against the ends of the head 27 so that when the carrier plate 13 receives an angular movement, the combined actions of the projection 24 and head 27 on the slipper serve to impart a corresponding sliding movement of the slipper on the contiguous surface of the supporting member 10.

For holding the stop 24 in permanent contact with the member 10, there is mounted on the rear side of the said member a light spring consisting of a wire 34. This wire is coiled around a post 35 on the member 10, at the side of the boss 12 remote from the slot 26, and its free ends lie in the tapering gaps between the slipper 29 and the inclined edges 28 of the head 27. As the free ends of the spring wire tend to move towards each other they set up a wedging action on the head 27 which holds the stop 24 in permanent contact with the member 10. Moreover, due to the position of the post 35 any angular movement of the carrier 13 relative to the member 10 will result in movement of the free ends of the spring wire in the gaps between the slipper 29 and the edges 28, thus avoiding risk of seizure.

The arrangement is such that the interaction of the stop 24 and supporting member 10 resists the impact of the cam 20 on the tip 19 of the arm 16, each time that the contact pieces 14 and 18 are separated, and so prevents tilting of the interrupter carrier 13 relatively to the supporting member.

The invention is not, however, limited to the particular example above described as subordinate details may be varied. Thus the abutments 22, 23 and 24 may be formed on or attached to the supporting member, and instead of the wire spring 34, any other convenient spring means may be provided, such as a spring blade secured to the head 27 and having a free end which bears on the rear face of the member 10.

Having thus described my invention what I claim as new and desire to secure by Letters Patent is:

1. An electric current interrupter for an engine spark-ignition apparatus, comprising in combination a fixed supporting member, a contact carrier having angular freedom of movement relative to said supporting member, a spring-loaded arm pivotally mounted on said carrier, a pair of mutually engageable contact pieces respectively mounted on said carrier and spring-loaded arm so that the latter tends to urge the contact piece thereon into contact with the other contact piece, a rotary cam arranged to act intermittently on said arm for effecting separation of said contact pieces, a triangular arrangement of three abutment pieces through the medium of which said carrier is supported by said supporting member, two of said abutment pieces forming fulcrum points about which said arm tends to tilt said carrier under the action of said cam, and the third abutment piece forming a stop for preventing tilting movement of said carrier in one direction about said fulcrum points, a projection extending from said carrier through an arcuate slot in said supporting member at a position adjacent said third abutment piece, a head on the outer end of said projection, and a spring acting between said head and supporting member for holding the stop formed by said third abutment piece in its service position, said third abutment piece being located on a radial

line extending from the axis of said carrier through the part of said arm on which said cam acts so that tilting of said carrier under the action of said cam is prevented by said third abutment piece.

5. An electric current interrupter according to claim 1, and comprising a slipper bearing against said supporting member and engaged by the projection on said carrier so as to be movable therewith relative to said supporting member, the head on said projection being shaped to provide between it and said slipper a pair of tapering gaps, and free ends of said spring being located in said gaps so as to exert a wedging action on said head.

10. An electric current interrupter according to claim 2, and comprising a post which is mounted on said supporting member, and about which said spring is coiled so that the free ends of said spring are caused to move in said tapering gaps during angular movement of said carrier relative to said supporting member.
